COMPUTING DEVICE

Dundred D. Evers, La Jolla, Calif., assignor to the
United States of America as represented by the
Secretary of the Navy

Application August 25, 1945, Serial No. 612,677

1 Claim. (Cl. 74—198)

1 The present invention relates to the ball type of computing devices.

An object of the invention is the provision of an improved construction for the ball type of computing devices.

Another object is the provision of an improved and simplified construction of the ball type of resolving mechanisms for eliminating difficulties due to misalignment.

A further object is the provision of a simple improved mechanism for the direct and accurate addition of vector components.

In the ball-type resolver or "Henrici" harmonic analyzer, a ball is driven by a roller bearing against a pole and the pressure of this driving roller is balanced by the reaction of a guide roller at the opposite pole. Output rollers are arranged around the equator of the ball. The term "equator" is here intended to mean a great circle of the ball, all points on which are equidistant from the poles. The "poles" are the points at which the axis of the equator touches the surface of the ball. Operation of the driving roller causes the ball to rotate about the diameter that is parallel to the axle of the driving roller, which can be so positioned as to change the direction in which the ball turns. It is necessary to provide an arrangement for keeping the guide roller axis parallel to that of the driving roller. Otherwise the effect of the two rollers is to force the ball to one side, that is, approximately in the direction of the axes of these two rollers, and thereby to increase the force exerted against some of the equatorial rollers and to reduce that impressed on others. Heretofore, it has been necessary to impose high contact pressures on the output rollers at the equator simply to prevent this lateral crowding of the ball from reducing the forces between ball and output rollers below the values required for good driving contact. This increased roller pressure increased the mechanical load on the device and thereby aggravated the difficulty. Additionally, prior-art devices also involve heavy gearing arrangements for aligning the axes of the guide and driving rollers.

In accordance with my present invention I avoid these limitations of prior-art ball resolvers by employing a caster-type guide roller. In the construction described the guide roller is incapable of exerting any lateral force on the ball, that is, any force in the direction of the guide roller axis. Consequently, no displacement reducing the forces on the equator rollers can occur.

In accordance with the present invention I also provide an improved ball computer capable

2 of reciprocal operation, in which the equatorial rollers are employed as drivers for introducing vector data components into the calculating device and the vector sum or solution is taken from a polar roller.

It will be understood that when the prior-art ball type of computer is operating in such fashion as to add two vectors and to determine the polar coordinates of the resultant, the equatorial rollers function as the driving rollers, one polar roller serves as the output roller, and the roller located in diametrical opposition to the output roller acts as a guide roller. The reaction of the guide roller balances the pressure of the output roller against the ball. Similarly, it is necessary to provide an arrangement for maintaining parallelism between the axes of the guide and output rollers. Otherwise, displacement of the ball would increase the force exerted on the ball by one of the driving rollers and reduce that exerted by the other. In prior-art devices it has been necessary to impose high contact pressures between equatorial driving rollers and ball and to provide heavy gearing arrangements for aligning the axes of the guide and output rollers in order to prevent ball displacement from reducing the forces between ball and roller below those required for good driving contact. I avoid these limitation of prior-art devices by using casters at both poles. The trailing angle of a caster then indicates the vector angle or direction of the vector sum or resultant and the speed of rotation of a caster roller indicates its magnitude or modulus.

One application of this arrangement is in the computation of course (Ct) and speed (St) of a target for the control of naval gunfire. Certain prior systems for determining these quantities have employed trial and error methods in accordance with which values were assumed for course and speed and checked by the calculating devices. For example, a calculating device would determine the range rate (dR) and bearing drift (dBr) that should result from the assumed values of course and speed. Then the officer operating the equipment would compare these computed values with the range rate and bearing drift actually observed and make further estimates for correcting the values first assumed. The difficulties and delays of such a process were aggravated by the circumstance that it was often difficult to determine which assumed quantity, whether for speed or course, ought to be revised for the next calculation. The present invention overcomes these difficulties because its method of calculation is direct and automatic so that it may

3

be employed in a system which requires no estimates of this character.

These and other objectives and advantages of the invention will be apparent from the following description taken in connection with the drawings in which:

Fig. 1 is a perspective view of a computing device embodying my present invention in a preferred form;

Figs. 2 and 3 are detail sectional views taken along line 2—2 of Fig. 3 and line 3—3 of Fig. 2, respectively;

Figs. 4 to 7, inclusive, are diagrams for explaining the operation of the device of Figs. 1 to 3;

Figs. 8 and 9 are elevation and plan views showing certain of the moving parts of a resolver embodying my invention; and

Fig. 10 is a mechanical schematic diagram of a computing system including the device illustrated in Figs. 1 to 3.

In Fig. 1 there is illustrated a device which vectorially adds two component quantities and determines the modulus or magnitude of the resultant vector quantity as well as the polar or vectorial angle of the resultant. A ball 10 has three rollers 12, 14 and 16 (Fig. 4) contacting it at its equator. All three rollers turn about horizontal axes. Rollers 12 and 14 are spaced 90° apart along the equator and constitute drivers by which velocity components are imparted to the ball. Roller 16 is an idler for holding the ball against the rollers 12 and 14.

As may be seen in Figs. 1 and 2 the ball 10 has an upper caster-roller 18, and a lower caster-roller 20, which contact it near the upper and lower poles respectively. The caster wheel 18 has a horizontal axle trunnioned in a bracket 22 which in turn is fixed to a trunnion bearing 24 the axis of which constructively passes through the center of the ball 10. Caster roller 22 is similarly supported so that the axis of its trunnion bearing constructively passes through the center of the ball. Trunnion bearing 24 carries a gear 26 which drives a plate or gear 28 that may be provided with an index (not shown) to indicate the angular position of the caster trunnion, that is, the direction in which the caster 18 trails. Gear 28 may also be used for transmitting this angle datum to other computing apparatus. This datum is the polar or vectorial angle of the resultant vector.

In order to indicate the modulus or magnitude of the resultant vector, which is determined by the speed of roller 18, any suitable conventional tachometer may be provided. For example, caster roller 18 periodically actuates a microswitch 32 by means of a cam and plunger best shown in Figs. 2 and 3. Roller 18 carries a four-sided cam 19. Trunnion 24 is hollow and has a pair of bearings 25 to permit a pin 34 to slide up and down therein. At its lower end this pin 34 carries a rigid arm 36 which rides cam 19, and at its upper end the pin drives against the operating plunger of the microswitch 32 the construction of which is shown, for example, in U. S. Patent No. 1,960,020. The switch actuates any suitable speed-indicating device (not shown).

The motion imparted to the ball 10 by the two driving rollers 12 and 14 consists of a rotation about a horizontal diameter and the consequent motion of the ball surface in the region of the upper pole will cause the caster roller 18 to trail in the direction of the plane of rotation. Accordingly, the rotated position assumed by the caster trunnion 24 indicates the direction of rotation

4

of the ball. The caster roller 20 behaves similarly but of course will assume an opposite orientation, as shown in Fig. 1. Caster 20 is simply a guide-roller for holding the ball against the upper caster roller 18. Since it is free to trail, the guide-roller can roll freely on the ball 10 for any direction of rotation that the two driving rollers 12 and 14 can give it.

The rotation of the roller 18 drives cam 19 which in turn cyclically lifts the pin 34 to operate the microswitch 32. The frequency meter 91 receiving electric impulses generated by the microswitch may be employed to provide an indication of the speed of roller 18 and therefore of the speed of rotation of the ball 10.

The diagrams of Figs. 4 and 5 show how the component speeds of rollers 12 and 14 add as vectors. As has already been pointed out, any surface speeds X and Y imparted to the ball 10 by the rollers 12 and 14 cause the ball 10 to turn about some horizontal axis such as the axis 42 in Fig. 4. Accordingly, the track or path of contact of roller 12 on the surface of ball 10 is a circle which appears in projection as the dotted line 44 in Fig. 4 and similarly the track of roller 14 on the ball is a circle which appears in projection as the dotted line 46. The track of roller 18 is a circle which appears as the dotted line 48 and constitutes a great circle of the ball. For the purpose of this explanation the angular position of the caster trunnion is indicated by the angle T measured from the reference line 50. By inspection of the diagram it is clear that angle B equals Angle T and that angle A equals 90° minus angle B. Accordingly, the ratio of the radius of circle 44 to the radius of the ball 10 equals the sine of A, which equals the cosine of T. Also the ratio of the radius of the circle 46 to the radius of the ball equals the sine of B, which equals the sine of T. Accordingly if X equals the surface speed of roller 12, Y the surface speed of roller 14, and Z the surface speed of caster roller 18, then X equals Z times the cosine of T, and Y equals Z times the sine of T. Therefore, the speeds of rollers 12 and 14 add vectorially as indicated in the parallelogram of Fig. 6. Their vector sum or resultant vector is the speed of caster 18. The vector angle of the resultant is the angle of trunnion 24. This speed and the angle fully indicate the polar coordinates of the resultant vector.

This relationship between the roller speeds, whereby velocity components are added, holds also for all other conditions and the resulting angular positions of the caster roller 18. For example, if the direction of rotation of roller 12 is the reverse of that indicated in Fig. 4, the conditions shown in Fig. 7 result. If it is kept in mind that the angle A is negative in Fig. 5, it will be seen that the same relations hold. The parallelogram of Fig. 7 corresponds to the conditions shown in Fig. 5.

Alternatively, the speed of caster roller 18 may be measured with gears and shafts, or by having the roller 18 drive a small electric generator 98 the voltage or frequency of which indicates the speed. However, since roller 18 turns in only one direction relative to bracket 22 a cam 19 such as is shown in Figs. 2 and 3 is generally satisfactory. Although the angle between the two rollers 12 and 14 is 90° in the specific construction illustrated in Figs. 1 to 3, it may be given other values to meet the needs of other computations.

Fig. 10 illustrates schematically a mechanical system, including the ball computer of Figs. 1

to 3, for computing the course (C_t) and speed (S_t) of a target ship. Observation of the target by other devices aboard ship produces two items of data: the bearing (B_r) of the target from the observer, and the range (R) of the target, that is, its distance from the observer. Successive observations of range by still other devices aboard ship generate the range rate, (dR) that is, the speed in knots or other units at which the range decreases or increases.

Successive observations of bearing by the last named devices generate the bearing drift (aB_r) in degrees per minute of time, or in other convenient units. The range rate and the range-times-bearing-drift ($RdBr$) constitute components of target velocity along the line of sight (Y_t) and across it, (X_t) but they are components of velocity relative to the observer's ship, so that in order to obtain the actual speed (S_t) and course (C_t) of the target, it is necessary to include also in the calculations the components of velocity of the observer's ship along (Y_o) and across (X_o) the line of sight to the target.

The Fig. 10 system comprises: (1) a resolver having a mode of operation, reciprocal to that of the Figs. 1 to 3 embodiment but the same as that of the Figs. 8, 9 embodiment and including elements 60, 62, 64, 66, 68 and 70; four mechanical differentials 72, 74, 76 and 78; and a computer in accordance with the Figs. 1 to 3 embodiment, the same elements having the same reference numerals.

In Fig. 10 a ball 69 is driven at a speed proportional to that (S_o) of the observer's ship by a single driving roller 62, the angle of the axis of which is controlled by gears 64 and 66 in accordance with the relative bearing (B_r) of the target, that is, the number of degrees of angle that the line of sight to the target lies off the course of the observer's ship. Driving roller 62 bears against a pole of the ball. Two output rollers 68 and 70 have their axes lying in the plane of the ball's equator and bear against the ball at points 90° apart on the equator.

Roller 68 turns at a speed proportional to the component of observer's velocity (X_o) across his line of sight to the target. This rotation is combined in a differential 72 with the product of range and the "drift of true bearing" ($RdBr$), to supply to roller 12, the component of target velocity across the line of sight (X_t). Similarly, the speed of roller 70 is proportional to the component of observer's velocity (Y_o) along the line of sight and is combined in differential 74 with the range rate (dR) to drive roller 14 at a speed proportional to the component of target velocity (Y_t) along the line of sight.

Since the component speeds thus supplied to ball 10 by the rollers 12 and 14 constitute the actual velocity components of the target along the line of sight and across it, the angle taken up by the caster roller 18 is the angle θ between the target course and the line of sight (LOS) from the observer. The speed of roller 18 is proportional to the actual speed (S_t) of the target.

Relative bearing (B_r) information is supplied not only to gear 66 but also to differential 76 where it is combined with observer's course (C_o) to provide true bearing (B) of the target, that is, the angle between line of sight and true north. Differential 78 then combines the true bearing (from differential 76) with the angle θ between target-course and line of sight (LOS) (from gear 28) to provide target course (C_t) (as measured from true north).

Figs. 8 and 9 show a ball resolving mechanism

embodimenting the present invention. A ball 80 has three rollers 82, 84 and 86 engaging it at its equator, all three of which turn about horizontal axes. Rollers 82 and 84 are spaced 90° apart along the equator and constitute output rollers from which the velocity components resolved by the mechanism are taken off. Roller 86 is an idler for holding the ball firmly against the rollers 82 and 84.

- 10 At the upper pole or top of the ball 80 is a driving roller 88 whose shaft 89 is trunnioned in a ring 90. This ring turns about an axis which constructively passes through the center of the ball 80 to swing the axis of the roller 88 while 15 keeping it perpendicular to the polar diameter of the ball. Ring 90 is rotated by a gear 91. Fixed to the same shaft 89 as roller 88 is a bevel gear 92 which is driven by a second bevel gear 93. Gear 93 is centered with respect to ring 90 so 20 as to drive the roller 88 regardless of the orientation of its axle 89. Supporting the ball 80 at its lower pole is a caster guide-roller 94, the trunnion axis 96 of which constructively passes through the center of the ball 80.
- 25 In operation, the roller 88 is driven at a speed proportional to the magnitude of the vector (such as S_o) that is to be resolved into rectangular components, and the angles that its axle 89 makes with the axes of the rollers 82 and 84 are 30 set equal to the angles by adjustment of ring 90 (such as B_r and 90°— B_r) between that vector and the direction axes of the reference frame of cartesian coordinates in which the components are to be taken. The rotation of the ball 80 then 35 drives output rollers 84 and 82 at speeds proportional to the required velocity-components (such as $S_o \sin B_r$ or X_o and $S_o \cos B_r$ or Y_o). The caster 94 turns freely in its trunnion 96 and therefore trails freely.
- 40 It will be noted that elements 60, 62, 64, 66, 68 and 70 schematically represented in Fig. 10 correspond respectively, to elements 80, 88, 89, 90, 91, 84 and 82 illustrated in Figs. 8 and 9.

It is thus seen that my invention provides 45 simple and reliable mechanism for resolving a vector into its rectangular components or for adding vector components and obtaining the magnitude and direction of their sum. It will be apparent that the invention is not limited to 50 any specific embodiment but rather is capable of many modifications and variations and is limited only in accordance with the scope of the prior-art and the appended claim.

I claim:

- 55 In a computing device for determining the magnitude and direction of the vector quantity which is the resultant of two rectangular component vector quantities, a ball, a plurality of rollers rotatable about axes lying in an equatorial plane of the ball and having rolling engagement with the ball at spaced sections of an equatorial line defined by the intersection of said plane with the surface of said ball, two of said equatorial rollers having their axes disposed in perpendicular directions and constituting input rollers provided with drive means for imparting rotation to the ball at rates commensurate with the magnitudes of said component vector quantities, two casters supported for rotation about the polar axis normal to said equatorial plane, said casters having their roller axes laterally offset from their caster axes and having their rollers trailing in rolling engagement with the ball at opposite polar regions surrounding said polar axis, means 60 connected to one of said casters for indicating
- 70
- 75

7

the direction of trail of said caster and thus the direction of said vector quantity to be determined, driven means, and means transmitting rotary motion from one of said caster wheels to said driven means to drive said driven means at a rate commensurate with the magnitude of said vector quantity to be determined.

DUNDRED D. EVERSON.
